UNITED STATES PATENT OFFICE.

GEORGE C. SIEBERT, OF CHICAGO, ILLINOIS.

METALLIC PISTON-RING.

1,223,296.

Specification of Letters Patent. Patented Apr. 17, 1917.

Application filed October 12, 1916. Serial No. 125,200.

To all whom it may concern:

Be it known that I, GEORGE C. SIEBERT, a citizen of the United States, and a resident of the city of Chicago, in the county of Cook and State of Illinois, have invented a certain new and useful Improvement in Metallic Piston-Rings; and I do hereby declare that the following description of my said invention, taken in connection with the accompanying sheet of drawing, forms a full, clear, and exact specification, which will enable others skilled in the art to which it appertains to make and use the same.

My invention relates generally to improvements in metallic piston rings; and it consists, essentially, in the novel and peculiar combination of parts and details of construction, as hereinafter first fully set forth and described and then pointed out in the claim.

This invention has for its object the production of a very efficient and serviceable metallic piston ring for steam engines, gas engines, internal combustion engines, pumps, and all other machines in which a piston, operating in a cylinder, or steam chest is employed.

In piston rings of this nature it is essential that they shall make the piston as nearly fluid tight as it is mechanically possible to make them, and that they shall be expandible to compensate for wear. I accomplish these objects by the construction disclosed in the drawings already referred to, and in the following description of my invention.

In these drawings, Figure 1 is a plan of an expanded piston ring according to my invention. Fig. 2 is an edge view of a portion of said piston ring. Fig. 3 is a plan of a fragment of said ring. Fig. 4 is a transverse sectional view on line 4-4 of Fig. 3. Fig. 5 is a like view on line 5-5 of Fig. 3. Fig. 6 is a plan view of a portion of the piston ring, illustrating the same in contracted condition. Fig. 7 is a fragmental view of a modified construction of my invention. Fig. 8 is a fragmental view of the piston ring, showing its condition after the first step of milling has been performed thereon.

It is evident that metallic piston rings are made in many different sizes, so that for the purpose of this disclosure, I have illustrated in Fig. 1, a piston ring of practically full size suitable for the motors of internal

combustion engines, especially for those employed in automobiles, launches, etc. This ring is first produced oversize as an endless band. It is then split transversely, and then the joints are formed therein, which, when the ring is contracted, will overlap, or interconnect, and then the ring is contracted and in this condition ground to exact external size to fit the cylinder in which it is to be used.

The effective qualities of such a ring reside in the proper construction of the joint in the ring, and this joint I produce in the following manner:

The endless ring heretofore mentioned is clamped in a milling machine and with a suitable milling cutter I split this ring and round off the end of the portion 12 thereof, as shown at 13, while at the same time I reduce the thickness of the ring at the end 12 for practically one half of its thickness, as indicated at 15, and then split this end longitudinally for some distance back of said end 12 to form a slot 14 therein. I then form at the opposing end 16, and in the face of the ring, two grooves 17, 18, thereby leaving between these grooves a tongue 19, which tongue fits into the slot 14 by a tightly sliding fit. The ends of the grooves 17, 18, are rounded, as shown at 20, to correspond to the curvature 13 at the end of the portion 12, so that when the ring is contracted and in the condition shown in Fig. 6, the joint is perfectly closed and visible.

It will now be noticed that the tongue 19 fits perfectly in the slot 14, and that, therefore, fluid cannot pass past this tongue; nor can it pass through the slot 14, so that under all conditions of use the joint in the ring will be practically fluid tight until the ring has been worn to such an extent as to render further use thereof practically, if not entirely impossible.

It is, of course, essential that this joint be made as accurately as possible, and with perfect machinery; and for this purpose I have designed special machines to produce this perfect work. The object of rounding the grooves 17, 18, at their terminals is to enable these grooves being readily formed with so-called milling tools or cutters; and the rounding of the ends 13 is done so that when the ring is contracted there will be no open joints therein.

A ring of the construction described costs

but a trifle more than the usual metallic piston ring having a diagonal or similar split or joint, while practical use has demonstrated the fact that my piston ring is far superior to any of the various rings now employed in engines of the type described, and with which I am acquainted.

This packing ring is admirably adapted for use in pumps, used in pumping hot fluids, in steam engine valve chests having piston valves, and for many other purposes.

In piston rings for larger engines than those usually employed in automobiles and similar vehicles, I may find it desirable to increase the number of tongues and slots; and in Fig. 7, I have illustrated a fragment of a piston ring in side view, which piston ring is supplied with two tongues and coacting slots. It is, however, evident that the number of tongues and coacting slots may be further augmented without departing from the scope of my invention and that the method of manufacturing such rings is precisely the same as that heretofore described, the only difference being that a suitable number of milling cutters mounted on a mandrel common to all the cutters are employed to produce the slots and tongues heretofore described.

I have heretofore stated that the second

milling operation on the piston ring consists in splitting the ring to produce the slot 14 therein, and that the third operation is to mill the grooves 17, 18, in the opposite end of the ring, but it is obvious that the order of procedure regarding these two operations may be reversed without departing from the scope of my invention.

Having thus fully described this invention, I claim as new, and desire to secure to myself by Letters Patent of the United States—

The method of manufacturing metallic piston rings, consisting in first producing an endless ring of larger diameter than the required finished ring, then splitting this ring crosswise and reducing the thickness of one end of said ring for some distance from said end, at the same time rounding this end, then splitting the ring at one end in the middle to form a slot therein, then milling grooves at the other end of said ring and leaving the ends of said grooves rounded to afford a tongue adapted to enter said slot, then contracting the ring, and finally reducing said ring to operative external size by grinding.

In testimony that I claim the foregoing as my invention, I have hereunto set my hand.

GEORGE C. SIEBERT.
